UNITED STATES PATENT OFFICE.

BENO SCHNITZER, OF AKRON, OHIO, ASSIGNOR TO LUFTSCHIFFBAU ZEPPELIN GESELLSCHAFT MIT BESCHRANKTER HAFTUNG, OF FRIEDRICHSHAFEN, BODENSEE, GERMANY.

DEVICE FOR GROUND TRANSPORTATION OF AIRSHIPS.

Application filed December 22, 1924, Serial No. 757,327, and in Germany January 7, 1924.

My invention relates to means for facilitating the transport of gas-inflated airships while they are being handled on the ground, especially when bringing them into or out 5 of a hangar.

According to my invention, a special kind of scaffold is provided, which is fastened to one of the cars and to the framework of the ship's body and which by its arrangement 10 gives opportunity for an additional number of men to take hold of the ship. This scaffold is so connected to car and ship's body that it may easily be brought into position and removed again. Thus, there is no 15 weight added to the ship while in flight, which is most important. Furthermore, the device is provided with wheels by which the ship will be supported after the device has been attached to it. These wheels will 20 facilitate ground transportation, especially if provided in such a way as to be capable of turning around a vertical axis which does not meet the wheels' horizontal axle, thereby allowing the wheels to swing in 25 compliance with the direction of movement. For the purpose of facilitating the fastening of the scaffold to the ship, special provisions are taken to automatically connect both together after the scaffold has 30 been moved in its place. This also means a saving in time which may be very valuable when housing a ship. On the other hand means are provided for instantly unlocking 35 the scaffold from the ship, which may be- 40 come necessary after having brought the shop out of the hangar. The lower frame- 45 work of the scaffold may also be made heavy by putting ballast on it to prevent it and the ship from being lifted in the air. To pro- 50 vide against injuries from pressure of the ship downwards on the scaffold this may be made resilient by means of springs or other suitable means. Such scaffolds according 55 to my invention may be made use of at any suitable part underneath the airship. Of course, their dimensions have to be chosen so as to meet the conditions prevailing in 60 every individual case.

Having given a general description of my 65 invention I now want to explain it in detail referring to the drawing in which an example is shown embodying my invention.

Fig. 1 is a side view showing a portion of the lower part of an airship, the forward

portion of a car suspended from the airship 55 and the device.

Fig. 2 represents the device, side view, but on a larger scale.

Fig. 3 is a front view of the device seen in the direction of arrow A in Fig. 2. 60

Fig. 4 is a top view of the device.

Fig. 5 is a fragmentary side view of the automatic gripping and releasing device for connection to an airship car, and Fig. 6 is a top view of the same. 65

Fig. 7 is a side view of the corresponding mechanism for connection to the ship's hull, and Fig. 8 is a front view of the same.

In Fig. 1, the lower portion of the airship is designated by the numeral 4, and 3 is a 70 portion of a gondola or car.

The main part of the device is its frame 1, at one end of which two arms 2 are provided. These arms 2 have openings at their ends which fit around horizontal bolts 5 75 sticking out from the car 3. At the other end of the frame 1 arms extend substantially vertically and are connected to corresponding parts or bolts 7 at the hull of the ship. These arms may be made resilient in their 80 longitudinal direction by providing tubes 6 sliding over rods 8 hinged to the frame 1 at 8', collars 10 serving to hold and press on springs 11. The lower parts of the tubes 6 are connected to each other by a cross bar 12 85 which supports the lever arrangements 13. Ropes 14 and 15 connect these levers to the release levers 16 and 17, respectively, situated on arms 2 and 6, respectively.

In Figs. 5 and 6 the arm 2 has a longitudinal slit. In this slit two levers 19 and 16 are pivoted, swinging around bolts 20 and 16', respectively. Both are held in the positions shown in Fig. 5 by springs 18 and 21, respectively. This position shows the bolt 5 90 of the car enclosed by the jaws of the mouth at the end of arm 2, especially the shape of lever 19 is firmly grasping around bolt 5. By operating the release lever 13 (Fig. 1) which may be done by pushing down handle 100 26 the ropes 14 and 14' will be tensioned. First rope 14 will turn lever 16 so as to free arm 19' from the projecting hook obstacle 30, later rope 14' will turn lever 19 downwards and release bolt 5. 105

A similar arrangement is shown in Figs. 7 and 8 for the releasing and automatic gripping device which is adapted to connect at

the ends of arm 6 to the ship's hull. Herebeing situated both on a car and on the levers 23 and 17 are held in position by framework of said airship. springs 24 and 25, respectively. They swing around pivots 22 and 17' respectively. A 5 pull on rope 15 will turn lever 17 so as to free arm 23', and a rope 15' will then pull and turn lever 23 so as to release bolt 7. Handle 26 (Figs. 1, 2 and 3) causing the above mentioned pulls on ropes 14, 14', 15 10 and 15' must be actuated downwardly when it is intended to unlock the scaffold from the ship. Locking of the scaffold to the ship may be effected by merely pushing the ends of the arms 2 and 6 of the scaffold against 15 the respective bolts 5 and 7 of the ship.

The frame 1 is provided with one or more wheels 9 situated not far from the car of the ship. This wheel is revolvable also around a vertical axle so as to be capable of 20 running in every direction. Furthermore additional wheels 28 may be provided for the purpose of facilitating the transport of the device itself before it is attached to the airship. It may serve the same purpose to 25 swing the arms 6 around pivot 8' into a horizontal position. Tension member 27 may be made use of in folding down and re-erecting arms 6. It will facilitate the handling of the device if horizontal handling 30 bars 31 are provided alongside both sides of the frame 1.

I want it understood that I do not limit myself to the example described and shown in the drawing, as many variations will 35 occur to persons skilled in the art.

What I claim is:

1. A device for transporting gas-inflated airships while on the ground comprising a frame and pressure resisting means for detachably connecting said frame both to a 40 car and to the framework of said airship.

2. A device for transporting gas-inflated airships while on the ground comprising a frame, handling means on said frame, and 45 pressure resisting means for detachably connecting said frame both to a car and to the framework of said airship.

3. A device for transporting gas-inflated airships while on the ground comprising a frame, ballast supporting means on said 50 frame, and pressure resisting means for detachably connecting said frame both to a car and to the framework of said airship.

4. A device for transporting gas-inflated airships while on the ground comprising a frame, a supporting wheel mounted underneath said frame, and pressure resisting 55 means for detachably connecting said frame both to a car and to the framework of said airship.

5. A device for transporting gas-inflated airships while on the ground comprising a frame, and pressure resisting means for detachably connecting said frame to predetermined 60 connecting members, said members

6. A device for transporting gas-inflated airships while on the ground comprising a frame, and means for detachably connecting 70 said frame to predetermined connecting members, said means being adapted automatically to secure said frame to said connecting members, said members being situated both on a car and on the framework of 75 said airship.

7. A device for transporting gas-inflated airships while on the ground comprising a frame, pressure resisting means for connecting 80 said frame to said airship, and means for releasing said frame together with said pressure resisting means from connecting members; said members being situated both on a car and on the framework of said airship.

8. A device for transporting gas-inflated airships while on the ground comprising a frame, and means for simultaneously releasing 85 said frame from connecting members to which it is connected, said members being situated both on a car and on the framework of said airship.

9. A device for transporting gas-inflated airships while on the ground comprising a frame, pressure resisting means for connecting 90 said frame to predetermined connecting members, and means for releasing said frame from said members, said members being situated both on a car and on the framework of said airship.

10. A device for transporting gas-inflated airships while on the ground comprising a frame, means for connecting said frame to predetermined connecting members, and means for simultaneously releasing 95 said frame from said members, said members being situated both on a car and on the framework of said airship.

11. A device for transporting gas-inflated airships while on the ground comprising a frame, and arms extending from said frame, said arms being provided with clutching 110 elements adapted to cooperate with corresponding elements both on the car and on the framework of said airship.

12. A device for transporting gas-inflated airships while on the ground comprising a supporting collapsible scaffold, said scaffold at one end having a clutching element for cooperation with a corresponding element on 120 a car of said airship and its upper end having a clutching element for cooperation with a corresponding element on the framework of said ship.

13. A device for transporting gas-inflated airships while on the ground comprising a supporting collapsible scaffold, said scaffold at one end having a clutching element for cooperation with a corresponding element 125 on a car of said airship and its upper end 130

having a clutching element for cooperation with a corresponding element on the framework of said ship, and a wheel mounted underneath said scaffold.

- 5 14. A device of the type described comprising a structure adapted for simultaneously supporting the car of a gas-inflated airship and the framework of said airship, the supporting members of said structure 10 being adapted to transmit pressure stresses; and a wheel mounted underneath said structure.

15. A device of the type described com-

prising a frame; means for transmitting stresses from the framework of a gas-inflated airship to said frame; means for connecting said frame to a car of said airship; and a wheel mounted underneath said frame.

16. A device of the type described comprising a frame; means for elastically transmitting stresses from the framework of a gas-inflated airship to said frame; means for connecting said frame to a car of said airship; and a wheel mounted underneath said frame.

BENO SCHNITZER.
